(57) **CLAIM**

The ornamental design for a teat engagement structure as shown and described.

DESCRIPTION

FIG. 1 is a top right front perspective view of a teat engagement structure;

FIG. 2 is a front elevation view thereof, to which a rear elevation view thereof is identical;

FIG. 3 is a left side elevation view thereof, to which a right side elevation view thereof is identical;

FIG. 4 is a top plan view thereof; and,

FIG. 5 is a bottom plan view thereof.

The uniform broken lines in FIGS. 1-5 illustrate portions of the teat engagement structure that form no part of the claimed design, while the dash-dot broken lines define the bounds of the claimed design and form no part thereof. The stippling/dot shading shows only contour gradients but does not show or claim any decoration, coloring, contrasting textures, or surface texture.
